[57] CLAIM

The ornamental design for a buckle with web adjuster, as shown and described.

DESCRIPTION

FIG. 1 is a perspective view of a buckle with web adjuster showing my new design;

FIG. 2 is a plan view;

FIG. 3 is a right side view with the opposite side view being a mirror image thereof;

FIG. 4 is a rear view;

FIG. 5 is a top view;

FIG. 6 is a bottom view;

FIG. 7 is perspective view of a buckle with web adjuster showing a second embodiment of my new design;

FIG. 8 is a plan view of the buckle of FIG. 7;

FIG. 9 is a right side view of the buckle of FIG. 7 with the opposite side view being a mirror image thereof;

FIG. 10 is a rear view of the buckle of FIG. 7;

FIG. 11 is a top view of the buckle of FIG. 7; and,

FIG. 12 is a bottom view of the buckle of FIG. 7.
